UNITED STATES PATENT OFFICE.

DAVID ROBERTS, OF GRANTHAM, ENGLAND.

VAPORIZER FOR INTERNAL-COMBUSTION ENGINES.

1,124,061.

Specification of Letters Patent.

Patented Jan. 5, 1915.

Application filed August 21, 1913. Serial No. 785,953.

To all whom it may concern:

Be it known that I, DAVID ROBERTS, a subject of the King of Great Britain, residing at Spittlegate Iron Works, Grantham, Lincolnshire, England, have invented new and useful Improvements in Vaporizers for Internal-Combustion Engines, of which the following is a specification.

My invention has reference to vaporizers or combustion chambers for hydro-carbon engines of the type wherein a neck or contracted passage connects the vaporizer to the cylinder.

The object of my invention is to improve the efficiency of engines of this class by effecting a better mixing of the hydro-carbon fuel and air contained in the vaporizer and cylinder, and at the same time a richer mixture in the part of the vaporizer adjacent to the neck or contracted passage, so as to insure ignition and also by the more efficient disposition and the better shape of the water cooling surfaces of the vaporizer. For this purpose I proceed as follows, that is to say, I form the contracted passage or neck in the rear end of the cylinder and either centrally along or inclined to the longitudinal axis thereof, the said rear end of the cylinder being water jacketed and formed with a flat face to which is secured in any convenient manner the hot part of the vaporizer which is of hemispherical or other suitable shape. The longitudinal axis of the said vaporizer hot part is arranged out of alignment relatively to the longitudinal axis of the neck or contracted passage, in such a manner that one wall thereof is flush or approximately flush with the corresponding side of the said neck or contracted passage. The passage or inlet through which the hydro-carbon fuel is injected is located in the wall of the hot part of the vaporizer and in any suitable position relatively to the flush wall thereof. For example, it may be placed in the wall opposite the said flush wall or at right angles thereto. Furthermore, in the outer wall of the rear end of the cylinder between the neck or contracted passage therein, and the inner wall of the hot part of the vaporizer farthest away from the aforesaid neck or contracted passage there is provided, either as a loose part or as an integral part, a crescent or other suitably shaped depression or flat surface the size or area of which is designed to provide the necessary surface and

capacity in the cool or water-jacketed part of the vaporizer.

Vaporizers constructed as above described enable a better mixture of fuel and air and a more efficient cooling and higher efficiency to be obtained than heretofore, these results being due to the arrangement of the hot part of the vaporizer relatively to the contracted passage or neck in the cylinder, the relative position of the fuel injection and the disposition and shape of the cool or water-jacketed surfaces.

To enable the invention to be fully understood I will describe it by reference to the accompanying drawings, in which:—

Figure 1 is an end view of one form of vaporizer constructed according to the invention. Fig. 2 is a horizontal section thereof. Fig. 3 is an end view illustrating a modified form of the vaporizer. Fig. 4 is a vertical section thereof. Figs. 5 and 6 are views similar to Figs. 1 and 2 respectively illustrating a further modification, and Figs. 7 and 8 are views similar to Figs. 3 and 4 respectively of still another modification.

a represents the cylinder which is provided with the water-jacket *b* at its rear part and *c* is the contracted neck or passage formed in the rear end of the cylinder which is made with the flat face *a'*.

d is the hot part of the vaporizer which is applied against, and secured to, the flat face *a'* upon the water-jacketed end of the cylinder.

e is the passage or inlet through which the hydro-carbon fuel is injected into the hot part *d* of the vaporizer.

In the construction illustrated in Figs. 1 and 2 the contracted neck or passage *c* is arranged centrally along the longitudinal axis of the cylinder *a* and the hot or unjacketed part *d* of the vaporizer is of approximately hemispherical shape and, as above described, its longitudinal axis is arranged out of alignment relatively to the longitudinal axis of the neck or contracted passage *c* so that its rear wall is flush with the corresponding wall or side of the said neck or passage *c* as is clearly to be seen from the drawing. The passage or inlet *e* for the hydro-carbon fuel is in this arrangement located at the side of the hot part *d* of the vaporizer opposite that which is flush with the contracted passage or neck *c* so that the oil is injected horizontally into the

said hot part *d* of the vaporizer and on to the side thereof which is flush with the wall or side of the passage *c*.

The form of vaporizer illustrated in Figs. 3 and 4 is similar to that described in Figs. 1 and 2, that is to say, the contracted passage or neck is axially arranged with respect to the cylinder *a* and the hot part *d* of the vaporizer is ranged out of alignment relatively to the contracted neck or passage *c*, the relative position of these two parts differing, however, in that the displacement of the vaporizer takes place from above downward instead of laterally so that it is now the upper wall of the hot part *d* of the vaporizer which is flush with the upper side of the contracted neck or passage *c*. Furthermore, the passage or inlet *e* for the introduction of the hydro-carbon fuel is placed laterally of the vaporizer hot part *d* as before so that the fuel is injected into the latter in a direction at right angles to that in which it is injected in the preceding arrangement.

In Figs. 5 and 6 there is shown an arrangement which is the same as that illustrated in Figs. 1 and 2 with the exception that the contracted neck or passage *c* in this case has its axis inclined to the longitudinal axis of the cylinder *a*.

Figs. 7 and 8 show a construction which is similar to that illustrated in Figs. 3 and 4 except that in the form here shown the contracted neck or passage *c* has its axis inclined to that of the cylinder *a*.

f is the crescent or like shaped depression which is provided in the outer wall *a'* of the rear end of the cylinder between the neck or contracted passage *c* and the inner wall of the hot part *d* of the vaporizer most remote from the said neck *c*. This depression, which may also be in the form of a flat surface, is of a size or area designed, as above stated, to provide the requisite surface and capacity to the cool or water-jacketed part of the vaporizer. It is shown in each of the four modifications illustrated.

As above described vaporizers made in the manner hereinbefore set forth possess a number of advantages in practice. For ex-

ample, they permit of a better mixture of fuel and air to be obtained than has hitherto been possible and at the same time a higher degree of cooling and as a result of these features a higher efficiency. It will be understood that such increased efficiency results from the special arrangement of the hot part of the vaporizer relatively to the neck or contracted passage and also to the position of the fuel injection relatively to these two parts and to the shape and disposition of the neck and water-jacketed surface.

Claims—

1. A vaporizer or combustion chamber for internal combustion engines, comprising a neck formed in the cylinder end and provided with a water jacket, a hot part provided upon the end of the cylinder and having its axis out of alignment with the axis of the neck, the hot part being so located that one side of the inner wall thereof lies flush with the corresponding side of the said neck and the opposite wall of said hot part lies beyond the opposite side of said neck, and means for directing the injected fuel against that portion of the hot part lying flush with the neck.

2. A vaporizer or combustion chamber for internal combustion engines, comprising a neck formed in the cylinder end and provided with a water jacket, a hot part provided upon the end of the cylinder and having its axis out of alignment with the axis of the neck, the hot part being so located that one side of the inner wall thereof lies flush with the corresponding side of the said neck and the opposite wall of said hot part lies beyond the opposite side of said neck, a cooling surface provided on the end of said cylinder between the neck and the wall of the hot part which extends beyond said neck and means for directing the injected fuel against that portion of the hot part lying flush with the neck.

DAVID ROBERTS.
